UNITED STATES PATENT OFFICE.

CHARLES G. BAUER, OF DETROIT, MICHIGAN, ASSIGNOR, BY MESNE ASSIGNMENTS, TO
JAMES K. LANNING, OF FALL RIVER, MASSACHUSETTS.

KNITTING MACHINE.

Application filed January 24, 1920. Serial No. 253,820.

To all whom it may concern:

Be it known that I, CHARLES G. BAUER, a citizen of the United States, residing at Detroit, in the county of Wayne and State of 5 Michigan, have invented new and useful Improvements in Knitting Machines, of which the following is a specification.

This invention relates to knitting machines and has for its primary object the 10 provision of a novel form of driving means for a battery of identical knitting mechanisms, the latter adapted to singly or collectively co-act with said means as the circumstances demand, and said means being 15 designed whereby the knitting mechanisms will be grouped thereabout in a compact manner to cause the machine to occupy small floor or factory space, while producing an arrangement and assemblage of instrumentalities which will render the machine capable 20 of producing an exceedingly large quantity of finished or commercial material.

The invention is adapted to be used in connection with knitting mechanisms of the 25 character shown in my Patent No. 1,260,954, dated March 26th, 1918, wherein means are employed for producing tubular knitted fabrics of the character intended to be used as a conduit for electric wires or for similar 30 purposes. In the present invention I propose to produce commercial tubular fabric capable of being used as shoe laces, electric wire coverings, conduits or the like, and I have combined a circular series of knitting 35 mechanisms arranged concentric with a friction disk, the latter acting as a direct source of motive power for all of said knitting mechanisms.

An important object of the invention re- 40 sides in the arrangement of a circular series of knitting mechanisms, combining therewith a corresponding number of tensioning mechanisms and combining with all of said mechanisms a means for simultaneously setting the same in motion so that a uniform tension will be set up against the fabric during the knitting operation.

With the above and other objects in view 45 which will appear as the nature of the invention is better understood, the same consists in the improved construction and novel arrangements of parts which will herein- 50 after be fully described and particularly pointed out in the claims.

In the accompanying drawings, has been 55 illustrated, a single and preferred form of the invention, it being, however, understood that no limitations are necessarily made to the precise structural details therein exhibited, but that changes, alterations and 60 modifications within the scope of the claims may be resorted to when desired.

Figure 1, is a side view of the machine with parts omitted for the purpose of clear- 65 ness.

Figure 2 is a section taken on line 2—2 of Figure 1.

Figure 3 is a section taken on line 3—3 of Figure 1, showing the tensioning mecha- 70 nism.

Figure 4 is a section taken on line 4—4 of Figure 3.

Figure 5 is an end view of the tensioning mechanism.

Figure 6 is a vertical section taken 75 through the knitting mechanism showing parts in full lines.

In practice, I provide a suitable frame 10 on which is mounted a centrally located driven shaft 11, the same disposed vertically 80 at its upper end with a pulley 12 adapted to be connected with a belt or other suitable power transmitting means so that rotary motion will be imparted to said shaft. Supported by the frame between the ends of 85 the driven shaft is a table 13 on which knitting mechanisms 15 are pivoted as at 16 so that they may be moved either toward or away from the driven shaft 11 for a purpose to be hereinafter explained.

Each of said knitting mechanisms is of 90 identical construction and except for certain alterations in construction, can be the same as the knitting mechanism shown in my Patent No. 1,260,954, granted March 26, 95 1918. These mechanisms each include a base bracket 17 which provides for the pivotal connection 16 previously referred to and extending through the bracket and secured thereto as at 18 is a guide tube 19 through 100 which the tubular fabric passes in a downward direction as the knitting operation progresses. Embracing a part of said tube 19 is a cam 20 having the customary needle actuating groove 21 for the lugs 22 of recip- 105 roating needles 23. The cam is secured at 24 to an outer sleeve 25 whose lower end is formed into a cylindrical enlargement 26,

the latter equipped with a friction surface 27 which is preferably formed of rubber. The table 13 is provided with arcuate slots 28 through which the lower ends of the tubes 19 extend. These slots open onto the periphery of the table as shown in Figures 1 and 2 so that any one of the several mechanisms 15 can be thrown into and out of active knitting positions as the occasion demands. 10 On the driven shaft is a friction disk 29, the same arranged in horizontal alignment with the friction surfaces 27 and as illustrated in Figure 2, the periphery of the disk 29 is arranged with such regard to the inner ends 15 of the slots 28 as to permit the surfaces 27 to be brought into direct contact with the periphery of the disk 29 when the knitting mechanisms are in active knitting positions. From this arrangement it will be observed 20 that the disk 29 serves as a common source of motive power for the entire group of knitting mechanisms 15 and that the arrangement provides for compactness so that the machine can be placed in a comparatively small floor space and yet be capable 25 of manufacturing an exceedingly large quantity of commercial material.

The brackets 17 of each of said mechanisms 15 is provided with a radial lug 30 which is adapted to be engaged by a keeper lug 31 formed on a pivoted latch 32 carried by the table 13. The latches are normally operable and can be singly actuated so that any one of the knitting mechanisms can be 35 thrown out of operation without disturbing any of the other mechanisms.

In order that a uniform tension can be placed upon the fabric as the latter is in process of manufacture, I provide each of said mechanisms 15 with an independent tensioning mechanism 33, the same consisting of a tilting frame 34 disposed directly beneath its mating mechanism 15 and pivotally supported from a bracket 35 carried by the table 13. The frame carries feed rolls 36 and 37 between which the tubular fabric A is adapted to be fed as the same is received from the knitting mechanism. The supporting shafts 38 and 39 of said feed 50 rolls are suitably journalled in the frame 34 and at one side of the latter said shafts are provided with intermeshing gear wheels 40 and 41 which operate to cause said feed wheels to draw the fabric A in a downward direction. The shaft 38 is provided with a 55 worm gear 42 which meshes with a worm 43 on a shaft 44. Said shaft 44 is also journalled in the frame 34 and it is provided with a friction wheel 45 which contacts with the driving face of a friction disk 46 on the driven shaft 11. At the opposite end of the frame is an arm 47 on which a counter balancing weight 48 is mounted. The disk 46 is superposed with respect to the friction 60 wheels 45 so that under the action of the

counter balancing weights 48, said wheels will be held in active contact with the driving face of said disk.

From the construction described it will be observed that the disks 29 and 46 are carried by the same driven shaft 11, and that power from the latter is simultaneously transferred to the respective knitting mechanisms and said tensioning mechanisms, causing the knitted fabrics to be operatively 75 conveyed away from said knitting mechanisms as the knitting process is in operation. The construction provides means whereby the texture of the fabric is even and consistent and the occasion for accidentally dropping the stitch during the knitting operation is reduced to a minimum. The weight 48 of each tensioning mechanism is adapted to exert its influence against the fabric A so that the same will be held under tension simultaneous with the operation of drawing the fabric from the knitting mechanism and also simultaneous with the operation of holding the wheel 45 in driving contact with the friction disk 46.

What is claimed as new is:—

1. In a knitting machine, a plurality of knitting mechanisms and their take-ups, each including a needle actuating friction disk, said mechanisms arranged in a circular series and a driving friction disk encircled by said mechanisms and arranged in driving relation to all the needle actuating disks thereof, and means for throwing any one of said knitting mechanisms respectively into and out of driving engagement with the driving friction disk while said disk is in driving engagement with the other of said mechanisms, and a product take-up-controlling friction-disk for said take-ups. 105

2. In a knitting machine, a plurality of shiftably mounted knitting mechanisms and their take-ups, each including a needle actuating friction disk, said mechanisms arranged in a circular series, a driving friction disk encircled by said mechanisms and arranged in driving relation to all the needle actuating disks thereof and means for independently shifting said mechanisms with relation to said driving disk to render one or a selected number of said knitting mechanisms respectively active and inactive while the driving disk is in operation, and a product take-up-controlling friction-disk for said take-ups. 110

3. In a knitting machine, a plurality of knitting mechanisms and their take-ups, each including a needle actuating friction disk, said mechanisms arranged in a circular series, a driving friction disk encircled by said mechanisms and arranged in driving relation to all the needle actuating disks thereof, means for independently shifting said mechanisms with respect to said driving disk to render one or a selected number 125

of said mechanisms respectively active and inactive while the driving disk is in operation, and means for maintaining relatively fixed positions of said mechanisms with respect to said driving disk and a product take-up-controlling friction-disk for said take-ups.

4. In a knitting machine, a plurality of pivotally supported knitting mechanisms and their take-ups, each including a needle actuating friction disk, said mechanisms arranged in a circular series, a driving friction disk encircled by said mechanisms and arranged in driving relation to all the needle actuating disks thereof, means on each of said mechanisms and means co-acting with said first means for actively retaining said needle actuating disks against said driving disk and a product take-up-controlling friction-disk for said take-ups.

5. In a knitting machine, a plurality of knitting mechanisms and their take-ups, each including a needle actuating friction disk, said mechanisms arranged in a circular series, a driving friction disk encircled by said mechanisms and arranged in driving relation to all the needle actuating disks thereof, a tensioning device for each mechanism, fabric feeding means constituting part of said device, and means between the driving disk and said feeding means and common to all said feeding means for controlling movements thereof in time with the action of the correlated knitting mechanism.

35 6. In a knitting machine, a plurality of knitting mechanisms, each including a needle actuating friction disk, said mechanisms arranged in a circular series, a driving friction disk encircled by said mechanisms and arranged in driving relation to all the needle actuating disks thereof, a weighted fabric tensioning device for each of said mechanisms and including driven rolls for feeding the fabric from the mechanism in time with the action thereof and a driving friction-disk common to all said tension devices.

7. A knitting machine comprising a circular series of knitting mechanisms, a power shaft, a needle actuating disk on said shaft, said mechanisms each having a friction disk in contact with the needle actuating disk, tensioning devices for said mechanisms and including means for feeding the fabrics from said mechanisms in time with the knitting actions thereof, and friction-drive mechanism between the shaft and said fabric-driving means and common to all of the latter for actively controlling the same.

60 8. In a knitting machine, a circular series of knitting mechanisms, a circular series of tensioning mechanisms, and friction driving mechanism common to all of said knitting mechanisms and also common to all of said

tensioning mechanisms, the tensioning mechanisms related to the knitting mechanisms so as to uniformly feed the material from said knitting mechanisms in time with the knitting operation.

9. In a knitting machine, a plurality of knitting mechanisms arranged in a circular series, a plurality of tensioning mechanisms arranged in a circular series associated with said knitting mechanisms, a power shaft, friction disks carried by said shaft for respectively operating the knitting mechanisms and said tensioning mechanisms, and means for respectively throwing said knitting mechanisms into and out of driving engagement with the operating device of said shaft.

10. A knitting machine comprising, a knitting mechanism, needle actuating means therefor, a tilting tensioning mechanism including a plurality of driven rolls and a power transmitting shaft operatively connected with the rolls, a friction wheel on said shaft, a driven friction disk, and weight means on the tension mechanism for holding the friction wheel of the power transmitting shaft against said driven friction disk.

11. In a knitting machine, a circular series of knitting mechanisms, a tensioning mechanism associated with each of said knitting mechanisms to exert a constant drag on the materials as they leave said knitting mechanisms, and a driving shaft common to both mechanisms and including a pair of friction disks co-acting therewith to transmit driving motion to all of said knitting mechanisms and their tensioning mechanisms.

12. A knitting machine comprising a knitting mechanism, a tilting tensioning mechanism, said tensioning mechanism operating to exert a uniform continuous drag on the material as it leaves said knitting mechanism, a driving shaft, friction devices on the shaft respectively co-acting with the aforesaid mechanisms to transmit motion thereto, the tilting tensioning mechanism having a friction wheel engaging its co-acting friction device on said shaft.

13. In a knitting machine, a driving shaft, superposed disks, a knitting mechanism adjustably mounted with relation to the upper disk and provided with means adapted when the mechanism is adjusted to one position to engage with said disk so that power from the disk is taken into said mechanism, and a tilting tensioning mechanism co-acting with the knitting mechanism to induce a constant drag on the material as the latter leaves the knitting mechanism, said tensioning mechanism including a set of rolls between which the material passes as it leaves the knitting mechanism, and an

actuating shaft for the rolls, the shaft having a friction wheel engaging with the lower one of said friction disks.

14. In combination, a series of knitting mechanisms, a corresponding series of tensioning mechanisms arranged in a circular series, friction driving mechanism, common to said knitting mechanisms and a friction driving mechanism common to said tensioning mechanisms, the latter being related to the knitting mechanisms so as uniformly to feed the material from said knitting mechanisms in time with the knitting operation.

15. In combination, a series of knitting mechanisms arranged in a circular series

and adapted to be frictionally driven, a tensioning mechanism associated with each of said knitting mechanisms to exert drag on the fabrics as they leave said knitting mechanisms and adapted to be frictionally driven, a driving shaft for said mechanisms and two friction drive disks operated by said driving shaft, one of said disks transmitting driving motion to said knitting mechanisms and the other of said disks transmitting driving motion to said tensioning mechanisms.

In testimony whereof I have affixed my signature.

CHARLES G. BAUER.
